UNITED STATES PATENT OFFICE.

JOSEPH H. JACKSON, OF NEW YORK, N. Y.

METER-LOCK.

No. 927,146.

Specification of Letters Patent.

Patented July 6, 1909.

Application filed November 14, 1908. Serial No. 462,600.

To all whom it may concern:

Be it known that I, JOSEPH H. JACKSON, a subject of the King of Great Britain, and a resident of the city of New York, borough 5 of Brooklyn, in the county of Kings and State of New York, have invented a new and Improved Meter-Lock, of which the following is a full, clear, and exact description.

This invention relates to locks for electric 10 meters and similar devices, and more particularly to a meter having a removable casing wall or closure and a stud extending through the wall to the outside of the casing, and a locking bar removably secured at one end to 15 the casing and serving to secure the wall, and keepers, one of which is loosely mounted upon the stud, the latter at the same time receiving the locking bar to hold the same in position, the second keeper having a 20 threaded opening by means of which it can be screwed upon the stud, the keepers and the locking bar having registering openings which receive a suitable seal to prevent unauthorized opening of the meter.

An object of the invention is to provide a 25 simple, inexpensive and durable lock for electric meters and similar devices by means of which unauthorized opening of the meter and tampering therewith is prevented, and 30 which, when the seal is broken can be easily released and can easily be replaced.

A further object of the invention is to 35 provide a device of the class described, which cannot be opened without destroying the seal or the lock itself, with which various kinds of seals can be employed, and which is applicable to different forms of meters.

The invention consists in the construction 40 and combination of parts to be more fully described hereinafter and particularly set forth in the claims.

Reference is to be had to the accompanying 45 drawings forming a part of this specification, in which similar characters of reference indicate corresponding parts in all the views, and in which

Figure 1 is a front elevation of an electric 50 meter showing an embodiment of my invention applied thereto; Fig. 2 is a transverse section on the line 2—2 of Fig. 1; Fig. 3 is an enlarged front elevation of a part of a meter showing a modified form of my invention applied thereto; Fig. 4 is a transverse section on the line 4—4 of Fig. 3; Fig. 5 is 55 a front elevation of the lower part of a meter of different type, showing a further modified

form of my invention applied thereto; Fig. 6 is a longitudinal section on the line 6—6 of Fig. 5. Fig. 7 is an edge view of an end of the locking bar showing a modification.

60

Before proceeding to a more detailed explanation of my invention, it should be clearly understood that while the same is particularly useful in connection with electric meters by means of which the amount 65 of electric current used by the consumer can be determined, it can also be advantageously employed for other purposes in which it is desired to lock a casing so that an unauthorized entrance into the casing without leaving indications of such entry is prevented. Furthermore, the application of my invention need not be limited to casings or similar structures, in fact it can be employed for any purpose in which it is desired to lock 70 a closure, provided that the closure has projecting through it a stud, and that if the withdrawing of the closure from the stud is prevented the closure cannot be opened. If such is the case, my meter lock can be suitably applied to the stud so that the closure 75 cannot be withdrawn without destroying the lock, unscrewing the keepers from the stud, or breaking the seal which is employed in connection with the lock.

85

Any suitable form of seal can be used with my meter lock, and as shown for example, the seal may consist of a porcelain body having a U-member inserted therein and which is so formed that the member cannot be withdrawn without rupturing the body. Again, it may consist of a shank of soft metal which can be inserted through the opening provided therefor in the lock, and upon which is pressed a soft metal head so 90 that the shank cannot be withdrawn without breaking the same or removing the head. Needless to say, any other suitable type of seal can be employed.

95

When applied specially to some forms of 100 meters, the bar of the lock extends across the inscription plate of the meter and thus tends to conceal certain of the inscriptions on the plate. As it is often necessary to see these inscriptions, I provide bars of special 105 form which do not interfere with the reading of the inscriptions on the plate, and which therefore do not have to be removed when it is necessary to ascertain for example, the amperage or voltage of the meter.

110

Referring more particularly to the drawings, 10 represents the casing of a meter hav-

ing a removable casing front or wall 11, which when removed discloses the mechanism within the meter, which carries the registering dials 12 of the same. The meter 5 casing or body has spaced threaded studs 13 and 14 which extend through suitable openings 15 and 16 respectively in the wall 11, so that they project to the outside of the casing. It is necessary to slip the wall from 10 the studs in order to open the casing.

In the form of my invention shown in Figs. 1 and 2 I employ a bracket 17 having a threaded opening 18 therethrough by means of which it can be screwed upon the 15 stud 13. The bracket has a laterally offset part 19 through which extends a slot 20. I employ a locking bar 21 adapted to be inserted through the slot 20 and having a bifurcated end 22 which straddles the stud 13 when the bar is in position, as is shown most clearly in Fig. 1. As the bar extends across the inscription plate 23 of the meter it has a cut-away part, or slot, 24 which permits a certain inscription on the plate to be 25 seen through the bar. Near the opposite end, the bar has an opening 25 which is not threaded and which therefore loosely receives the stud 14.

I employ an inner keeper 26 which consists of a flat, preferably slightly tapered member having near one end an opening 27 by means of which it is loosely mounted upon the stud 14 underneath the bar. The 30 thickness of the keeper 26 approximates the thickness of the bracket 17 under the bar, and the latter is consequently evenly spaced from the wall 11 and the inscription plate 23. Near the free end, the inner keeper has an opening 28 therethrough. I also use an 35 outer member 29 which near one end has a threaded opening 30 by means of which it can be screwed upon the stud 14 to hold the locking bar in place. Near the opposite end, the outer keeper has an opening 31 there- 40 through which registers with an opening 32 in the locking bar and with the opening 28 of the inner keeper. The openings 28, 31 and 32 receive the seal 33 by means of which the lock is secured.

In the form of my invention shown in Figs. 3 and 4, I employ a U-shaped bracket 34 which at the end has threaded openings 35 by means of which it can be screwed upon the stud 13. The U-shaped bracket 34 45 replaces the bracket 17 and is loosely mounted in an opening 36 at the end of a locking bar 37. The extremities of the U- 50 bolt are preferably enlarged and the opening 36 is therefore of key-hole form to permit the bracket to be inserted through the opening. The locking bar 37 has intermediate its ends an offset preferably curved part 38 which permits certain desired inscriptions of the face plate 23 to be disclosed 55 to view. At the end remote from the bracket

34 the bar 38 is similar to the bar 21 and cooperates with an inner and an outer keeper 26^a and 29^a respectively, as does the bar 21. As is shown in Figs. 3 and 4, I may employ 70 a seal consisting of a shank 39 of lead or other soft metal, having a head 40. The shank is inserted through the openings 38^a, 31^a and 32^a and projects beyond the inner keeper. A block 41 or other body of soft metal is pressed upon the projecting end of 75 the shank to complete the seal.

The form of my device shown in Figs. 5 and 6 is used with a meter casing 42 having a removable wall 43 through which projects a stud 44. Near the lower end of the casing 80 the stud is threaded and receives a jewel guard or locking bar 45 which is pivoted or otherwise secured to the casing at the end of the bar remote from the stud 44. The bar has an opening 46 which is not threaded and 85 through which the stud can project. An inner keeper 47 having a smooth opening 48 is loosely mounted upon the stud underneath the bar 45, and an outer keeper 48^a having a threaded opening 49 is screwed upon the 90 stud at the outside of the bar 45 to hold the same in place. The keepers and the bar have registering openings 50 to receive the seal.

The locking bar as shown in Fig. 7, may have an extension 51 to take the place of the 95 inner keeper 26, the extension being as thick as the bracket 17.

Having thus described my invention, I claim as new, and desire to secure by Letters Patent:

1. The combination with a casing having a removable wall and a projection extending through said wall to the outside of said casing, of a locking bar removably arranged upon said casing and engaging said projection, a keeper engaging said projection, said bar and said keeper being formed to receive a seal whereby said bar cannot be removed to permit said casing to be opened without removing said seal, and means for holding 100 said bar at a point remote from the seal.

2. The combination with a casing having a removable wall and a threaded projection extending through said wall to the outside of said casing, of a locking bar removably 105 arranged upon said casing and loosely engaging said projection, keepers, one of said keepers loosely engaging said projection, the other of said keepers being screwed upon said projection, said keepers and said bar 110 being formed to receive a seal to hold said keepers and said bar in place upon said projection, and a bracket for removably holding said bar upon said casing at a point remote from the seal.

3. The combination with a casing having a removable wall and a threaded projection extending through said wall to the outside of said casing, of a locking bar removably secured at one end to said casing and at the 115

other end having an opening loosely engaging said projection, an inner keeper having an opening and loosely mounted by means of said opening upon said projection underneath said bar, and an outer keeper having a threaded opening whereby said outer keeper is screwed upon said projection at the outside of said bar, said keepers and said bar having openings adapted to receive a seal.

4. The combination with a casing having a removable wall, and spaced threaded studs extending through said wall to the outside of said casing, of a locking bar removably arranged upon said casing, a bracket secured upon one of said studs and holding said bar in place at the end adjacent to said stud, said bar engaging the other of said studs, and a keeper having threaded engagement with the other of said studs; said bar and said keeper being formed to receive a seal whereby said bar cannot be removed to permit said casing to be opened without removing said seal.

5. The combination with a casing having a removable wall and spaced threaded studs projecting through said wall to the outside of said casing, of a locking bar, a bracket screwed upon one of said studs and formed to receive said bar, said bar being adapted to engage the other of said studs, and a keeper screwed upon the other of said studs and arranged to hold said bar in engagement with the other of said studs, said bar and said keeper being formed to receive a seal.

6. The combination with a casing having

a removable wall and spaced threaded studs projecting through said wall to the outside of said casing, of a bracket having a threaded opening whereby it can be screwed upon one of said studs, said bracket having a slot, a locking bar having a bifurcated end adapted to be inserted through said slot whereby said bifurcated end can engage said stud, said bar having an opening adapted to receive the other of said studs, an inner keeper loosely mounted upon said other stud, under said bar, and an outer keeper screwed upon said other stud at the outside of said bar, said bar and said keepers having openings therethrough adapted to receive a seal.

7. The combination, with a casing having a removable part and a projection extending through said part to the outside of said casing, of a locking member arranged on said casing and engaging said projection, a keeper mounted upon said projection, said keeper and said member being adapted to receive a seal, said keeper serving to hold said member upon said projection, said keeper being removable from said projection by a turning movement, and a bracket for removably attaching said member to said casing so that said member cannot be turned with said keeper when the seal is in position.

In testimony whereof I have signed my name to this specification in the presence of two subscribing witnesses.

JOSEPH H. JACKSON.
